UNITED STATES PATENT OFFICE.

LLOYD G. JOHNSTONE, OF NEW YORK, N. Y.

DOUBLE-JACK SWINGING BRACKET FOR GANG-SAWS.

No. 925,191.

Specification of Letters Patent.

Patented June 15, 1909.

Application filed July 16, 1908. Serial No. 443,763.

To all whom it may concern:

Be it known that I, LLOYD G. JOHNSTONE, a citizen of the United States of America, residing at New York, in the borough of the Bronx, county and State of New York, have invented certain new and useful Improvements in Double-Jack Swinging Brackets for Gang-Saws, of which the following is a specification.

10 This invention relates to an improved double-jack swinging bracket for gang-saws.

Gang-saws for cutting marble and other stones are suspended by jacks which are applied to the frames of the gang-saws. Owing 15 to the sand used in the sawing of the slabs, the suspension-pivots are rapidly worn out by friction, especially when there are no means for inclosing and protecting the same. This produces considerable expense as the 20 suspension-pivots have to be frequently replaced, whereby the work of the gang-saws is interrupted and delayed.

The object of this invention is to furnish an improved swinging bracket for gang-saws by 25 which the suspension-pivot is inclosed, and protected against wear and ingress of sand; and for this purpose the invention consists of a swinging bracket for gang-saws, which comprises a double jack, a pivot pin suspended in 30 the openings of the jack, a bushing placed on the suspension-pivot between the uprights of the jack, a box for inclosing the pivot consisting of three parts—a lower bearing block, an upper bearing block and a cover, the 35 lower bearing block and cover being connected by suitable bolts so as to inclose entirely the suspension-pivot and bushing, as will be fully described hereinafter and finally pointed out in the claims.

40 In the accompanying drawing, Figure 1 represents a perspective view of one corner of a gang-saw showing my improved double-jack swinging bracket thereon, Fig. 2 is a side-elevation of the swinging bracket, and 45 Fig. 3 is a vertical transverse section on line 3, 3, Fig. 2.

Similar letters of reference indicate corresponding parts.

Referring to the drawing, *a* represents one 50 corner of the frame of a gang-saw for cutting marble, granite and other stones. The frame of the gang-saw is suspended from four swinging brackets which are attached thereto and to which the suspension-rods *r* for the gang-saw are applied.

My improved swinging bracket is com-

posed of a double jack *b* which is provided with a base-plate *b*¹ and an angle-plate *b*², which extends downward so as to be attached to the frame of the gang-saw, as 60 shown in Fig. 1. The upper ends of the double jack *b* are provided with openings for receiving the suspension-pivot *c* of the swinging bracket which pivot is splined to the double jack. The suspension-pivot *c* is surrounded between the uprights of the double jack by a bushing *d* of steel or other suitable material, which is splined to the suspension-pivot *c* and thereby prevented from turning. The bushing *d* is surrounded by a casing, 70 lined with Babbitt-metal which consists of a lower bearing block *e* that is placed between the uprights of the double jack and provided with shouldered ends, an upper bearing block *e*¹ which bears on the upper part of the bushing and which is provided with a conical inlet-opening *e*² for conducting the lubricating material to the bushing, said conical opening being connected by a channel *e*³ in the upper bearing block with a supply-pipe *e*⁴ for the 80 lubricating oil. A cavity *e*⁵ is arranged in the lower bearing block to which the lubricating material is supplied from time to time by a channel *e*⁶ and a plugged pipe *e*⁷ at its outer end, as shown clearly in Fig. 2. 85 The upper bearing block which surrounds the upper part of the bushing is inclosed by a cover *f*, the side-walls *f*¹ of which extend over the upper side-walls of the double jack and the outer ends of the suspension-pivot *c*, as 90 shown in Fig. 3. The upper bearing block *f* is provided with shouldered ends *f*² which are recessed for surrounding the shouldered ends of the lower bearing block surrounding the lower part of the bushing. The shouldered ends *f*² of the cover *f* are connected by means of bolts *f*³ and nuts *f*⁴ with the shouldered ends of the lower bearing block so as to hold the same tightly in position on the bushing and permit the bearing blocks to swing 100 freely on the same. On the upper portion of the cover *f* is located a raised boss *f*⁵ that is preferably cast integral with the cover and provided in the center so as to form an interiorly threaded socket into which the suspension-rod *r* for the gang-saw is screwed. A 105 binding screw-nut *f*⁶ holds the suspension-rod *r* tightly in the socket after it is screwed home on the same.

The upper semicircular bearing-block is 110 tightly adjusted on the suspension-pivot by means of adjustable set-screws *g* provided

with jam-nuts g^1 below their heads, the jam-nuts and the socket for the suspension-rod r being covered by a cap h provided with an interior shoulder h^1 which fits over the socket 5 f^5 and which is held in position by a collar i on the cap and a set-screw i^1 passing through the collar, so as to hold the cap tightly in position and prevent the ingress of sand below the same to the set-screws g . The adjustable set-screws g serve to take up the slack of 10 the upper bearing block due to the wearing off of the Babbitt-metal lining of the same.

A uniform feed of lubricating oil is supplied to the upper bearing-block and from 15 the same along the bushing to the cavity in the lower bearing block, as shown in Fig. 2, while a separate supply of lubricating material is given from time to time to the lower bearing block.

20 The base of the double jack is tightly attached to the supporting frame of the gang-saw so as to form thereby a strong and reliable support for the suspension-pivot. As 25 the suspension-pivot, its bushing and the bearing blocks are fully protected by the cover and cap against the ingress of sand and as the bearing blocks are thoroughly lubricated during the oscillating motion of the blocks and cover, the gang-saw moves all 30 ways in a horizontal position without any parts except the bushing wearing out so that the frequent and expensive renewal of pivots of the swinging brackets heretofore in use is obviated and a better and superior suspension-bracket for the gang-saw obtained. The 35 bushing is the only part that requires renewal and that only at long intervals, when it can be replaced at comparatively small expense.

40 Having thus described my invention, I claim as new and desire to secure by Letters Patent:

1. A swinging bracket for gang-saws, comprising a double jack attached to the frame 45 of the gang-saw, a suspension-pivot splined to the upper part of the jack, a bushing surrounding the pivot between the uprights of the double jack, bearing-blocks surrounding the bushing, the lower bearing-block being 50 provided with shoulders at opposite ends, a cover the side-walls of which extend over the upper bearing block, the double jack and the ends of the suspension-pivot, the cover being provided with shoulders at opposite ends fitting 55 over the shouldered ends of the lower bearing-block, means for connecting the shoulders of the lower bearing-block with the shoulders of the cover, a socket at the upper end of the cover, and a suspension-rod inserted 60 into said socket.

2. A swinging bracket for gang-saws, con-

sisting of a double jack attached to the frame of the gang-saw, a suspension-pivot supported by said jack, a bushing surrounding said suspension-pivot, a lower bearing-block, an 65 upper bearing-block, a cover extending over the upper bearing-block, the side-walls of the jack and the ends of the suspension-pivot, means for connecting the ends of the lower bearing block with the ends of the cover, 70 means for lubricating the bearing-blocks independently of each other, means for setting the upper bearing-block, a socket on the upper part of the cover, a suspension-rod inserted securely in said socket, a cap extending 75 over the setting means for the upper bearing-block, and means for securing the cap in position.

3. A swinging bracket for gang-saws, consisting of a double jack attached to the frame 80 of the gang-saw, a suspension-pivot splined to said jack, a bushing surrounding said suspension-pivot and splined thereto, bearing-blocks surrounding said pivot, the lower bearing-block being provided with shouldered ends, a cover extending over the upper bearing-block, the upper part of the jack and the ends of the suspension-pivot, said cover being provided with shouldered ends, means for connecting the shouldered ends of the 85 lower bearing-block and the cover, means for lubricating the upper bearing-block, and separate means for lubricating the lower bearing-block independently of the upper bearing-block.

4. A swinging bracket for gang-saws, consisting of a double jack attached to the frame of the gang-saw, a suspension-pivot splined to said jack, a bushing surrounding said suspension-pivot and splined thereto, bearing-blocks surrounding said pivot, the lower bearing-block being provided with shouldered ends, a cover extending over the upper bearing-block, the upper part of the jack and the ends of the suspension-pivot, said cover being provided with shouldered ends, means for connecting the shouldered ends of the lower bearing-block with the shouldered ends of the cover, adjustable set-screws passing through the cover onto the upper bearing-block, a cap extending over said set-screws, means for securing the cap in position, and means attached to the cover for suspending the swinging bracket.

In testimony, that I claim the foregoing as 115 my invention, I have signed my name in presence of two subscribing witnesses.

LLOYD G. JOHNSTONE.
